TYPEWRITING MACHINE

Jesse A. B. Smith, Stamford, Conn., assignor to
 Underwood Elliott Fisher Company, New York,
 N. Y., a corporation of Delaware

Application December 29, 1933, Serial No. 704,425

24 Claims. (Cl. 197—127)

This invention relates to sheet-collating mechanism for use in typewriting-manifolding of individual bills with record-sheets, and particularly to machines of the kind which, instead of making a carbon copy that is an exact duplicate of the original copy in every way, types the items one under another upon one sheet, and at the same operation types one item by the side of another in a single line upon another sheet.

10 After the manifolding of each item, the sheets are recollated relatively to each other, and represented to the types with each sheet occupying a new position. The bill is line-spaced, so that the next item will be typed below the last; while the 15 record-sheet is not line-spaced but is shifted to one side, so that the next item will be typed on said record-sheet in the same line as the next previous item but in a different column. Thus the sheets are collated anew after the typing of 20 every item, and this recollation is effected expeditiously by improved means provided by the present invention.

It will be understood, since each transverse line of items on the record-sheet represents an 25 individual bill, that the vertical column-spaces of the record-sheet serve to classify like items of many bills.

The record-sheet may include column-spaces for certain items which are not required to be 30 entered on the bill, and which column-spaces are therefore to be skipped in the said recollating operations.

The bill is automatically line-spaced as a result 35 of its shift crosswise of the record-sheet. It is desired, however, when a record-sheet column is skipped, or when for any other reason the transverse spacing of the items typed on the record-sheet is not uniform, that there shall not appear 40 on the bill a corresponding skip-space in the vertically spaced items of said bill. In other words, it is desired that the items in the single column 45 on the bill-sheet shall be line-spaced automatically but uniformly, irrespective of whether or not the transverse spacing of said items on the record-sheet is uniform.

As a result of one feature of the present invention the recollating of the sheets for each item automatically follows from a simple tabulating-key operation, which may produce either corresponding spacings or dissentaneous spacings of 50 the items as they appear on the bill and record sheets.

In the patent to Farnham, Smith and Phelps 55 1,071,612, of August 26, 1913, a typewriting machine is provided with a letter-feeding carriage

for the record-sheet, said carriage being of special construction in order to work with another special carriage upon which is carried the bill-sheet, each carriage having an individual feed-roll-operating line-space mechanism for its work-sheet. In recollating the bill and record-sheet a tabulating mechanism operated by one key-mechanism is used for the record-sheet carriage, and another tabulating mechanism requiring the operation of another key-mechanism is used for 10 the bill-sheet carriage.

According to the present invention there is only one key-mechanism to be operated at each recollation of the bill and record-sheet, and consequently a substantial saving of time is effected.

In practicing the present invention use may be made of certain features of construction disclosed in my co-pending application 649,902, filed January 3, 1933, and adapted, by means of a novel organization herein set forth, for effecting item-spacings of agreeing or dissentaneous extents on the bill and record sheets. According to said application, a platen-carriage of conventional design, such as the Underwood, may be used to letter-feed, tabulate and line-space the record-sheet; and there may be mounted on said conventional platen-carriage a truck carrying the bill-sheet and moving along with said carriage for letter-feeding, said truck being guided on the carriage to move the bill-sheet crosswise of the record-sheet; and furthermore by means of a cam or inclined guide-rail, which cooperates with said truck, the bill-sheet is caused to be moved endwise for line-spacing at the same time that it is moved crosswise of the record-sheet.

For universal use with different forms of bill and record sheets, the said inclined guide-rail is made straight, and extends crosswise of the platen-carriage. It results therefore that the line-spacing movement of the bill-sheet effected 40 by means of said inclined guide-rail will be proportionate to the shift of the bill-sheet crosswise of the record-sheet. If the bill-sheet, for recollation, is moved from one column of the record-sheet to an immediately adjacent column, the 45 bill-sheet will be automatically advanced one line-space, but if said adjacent column should be skipped and the bill-sheet advanced to the next column on the record-sheet, the bill-sheet would be line-spaced two spaces, the resulting two line- 50 spaces between successive bill-sheet items producing an undesired skip-space on the bill-sheet.

The inclined guide-rail and the part which, to effect bill-sheet line-spacing, is in engagement therewith, are therefore newly arranged for the 55

purpose of the present invention so as to be capable of relative line-space retrograding movement, said movement being proportionate to the difference between an extent of bill-truck movement for shifting the bill-sheet one column or unit transversely of the record-sheet and an extent of bill-truck movement for shifting the bill-sheet beyond said column, as for record-sheet column-skipping. Thus the line-spacing advance 5 of the bill-sheet effected between the typing of the items will be uniform irrespective of the spacing of said items on the record-sheet.

The inclined guide-rail may be the member which is mounted for backward movement for 10 negativing any skip-space producing excess of line-spacing of the bill-sheet, the bill-truck being arranged to follow said inclined rail. The guide-rail, suitably guided on the record-sheet carriage, for its backward movement, is constantly urged backward by suitable means, such 15 as a spring, and its position is determined by means of stops mounted preferably on the typewriter-carriage. Other stops, also mounted preferably on said carriage, determine the position of the bill-sheet truck crosswise of the carriage, so that the bill-sheet may be collated with different columns of the record-sheet, said bill-truck being constantly urged contrariwise of the column-tabulating movement of said carriage by a spring. 20 Still other stops determine the positions of the record-sheet carriage in accordance with the several record-sheet columns.

Only one key-mechanism is brought into use following the typing of an item in a space on 25 the bill-sheet and in a corresponding column of the record-sheet, to effect recollation of the sheets for the next item. The collating organization is so arranged that as an automatic result of such use of the one key-mechanism, the record-sheet carriage is released from the usual letter-feeding escapement, and then arrested by means of one of the aforesaid carriage-stops; furthermore, as an automatic result of such use of the one key-mechanism, the bill-truck to 30 stops are actuated to cause the bill-truck to move relatively to the record-sheet carriage and in a direction contrary to the tabulating movement of said carriage, so that, in effect, the bill-sheet-item column is not shifted from the typing zone. Incidentally to such relative shift of the bill-sheet truck and record-sheet carriage, the bill-sheet truck is moved upwardly to line-space the bill-sheet by reason of following 35 said inclined rail.

A novel feature of organization resides in that as a result of the use of said one key-mechanism, the stops which control the position of the guide-rail are also caused to be automatically actuated if, by such use of said one key-mechanism, a 40 column of the record-sheet has been skipped, or if any otherwise-extended tabulation of the record-sheet has been effected. By such actuation of the guide-rail stops, the inclined guide-rail drops back, so that, in effect, the bill-sheet 45 is advanced only one line-space. Summarizing the foregoing, it may be stated that operation of said one key-mechanism not only effects tabulation of the record-sheet to a new column-position and recollation therewith of the bill-sheet, 50 and also line-spacing of the bill-sheet; but also automatically effects negativing of any skip-space producing excess in line-spacing movement of the bill-sheet resulting from said recollation.

75 A further feature of invention resides in em-

ploying a conventional tabulating key and stop mechanism, such as the Underwood, for the record-sheet carriage, and in utilizing, by means of suitable tappet-devices, the tabulating movement of the carriage for actuating the bill-truck 5 stops and the stops which control the line-spacing of the bill-sheet through the position of the aforesaid inclined guide-rail. Thus, not only is the organization simplified by the use of such conventional tabulating mechanism, but the latter may be of denomination-selecting type to further conduce to expediting the operation of recollating the bill and record-sheet, it being understood that, in said recollation, the bill-sheet column will not only be collated with the proper record-sheet column, but both columns will at the same time be positioned at the proper denomination for immediately starting the typing of the item.

Other features and advantages will hereinafter 20 appear.

In the accompanying drawings,

Figure 1 is a perspective view, showing the novel organization for collating the bill and record-sheet, the figure showing a record-sheet 25 carriage, the bill-sheet truck mounted on said carriage, and the novel means whereby the bill-sheet truck is line-spaced, and positioned transversely of the record-sheet carriage.

Figure 2 is a general top plan view, showing 30 the relative disposition of parts of the sheet-collating organization.

Figure 3 is a diagram, illustrating the arrangement of the different kinds of stops to be used when it is desired not to operate a tabulating 35 key repeatedly for column-skipping.

Figure 4 is a cross-sectional side elevation of the carriage and bill-truck, taken on a plane passing through the bill-truck to bring out details of construction, and also illustrating how a 40 bill-sheet is gaged and positioned in the bill-truck.

Figure 5 is a perspective view similar to Figure 1, and illustrates the record-sheet carriage advanced relatively to the bill-truck and the inclined guide-rail in a backward position resulting 45 from skipping a column on the record-sheet.

Figure 6 is a cross-sectional side elevation of the upper portion of the typewriter, the section being generally taken on a plane passing to the 50 near side of the bill-truck.

Figures 7 and 8 are diagrams, indicating the items on the bill-sheet uniformly spaced in a vertical column, while the items as they appear on the record-sheet are not uniformly spaced. 55 Figure 7 shows the skipping of one column at a time between certain items; and Figure 8 shows the skipping of more than one column. The diagrams also indicate by graphs the negativing of excess line-spacing of the bill-sheet when columns on the record-sheet are skipped.

Figure 9 is a perspective view, showing part of the means whereby the bill-sheet truck is guided for movement transversely of the record-sheet.

In the Underwood bookkeeping machine, Figure 2, to which the invention is applied, a typewriter 15 is mounted on a computing base 16, and has a letter-feeding carriage 17 mounting a platen 18 against which the usual singly operable type-bars, represented at 19, strike. Said platen 18 is journaled in a frame 20, supported for case-shift movement in a carriage-frame 21, guided by front and rear tracks 22, 23 for letter-feed travel effected by means of a carriage-motor 75

24 and escapement-devices 25 controlled by type-keys 26.

The carriage-tracks 22, 23 are part of a machine-frame 28, which also has a track 29 upon which runs a carrier 30 mounting a series of totalizer-heads 31. Said totalizer-carrier 30 is connected to the typewriter-carriage 17 by means of arms 32 reaching forwardly from the latter. Computing wheels of the totalizer-heads 31 are driven in a well-known manner by means of a master wheel 34 of a digit-indexing mechanism 33, indicated in Figure 6, and operated by means of the type-keys 26.

A record-sheet 35 and bill-sheet 36 are introduced to the platen-carriage, preferably by rear insertion and front insertion respectively. To this end, the platen-frame 20 may include a rear apron 31 curving under the platen, as seen in Figure 6, to form with the latter a rear insertion course for the record-sheet 35. A second apron 38 of the platen-frame 20 curves under the platen and first apron 31 to form a front insertion course for the bill 36 and has a flared edge 39.

To facilitate front insertion of a bill-sheet past said edge 39, there is used a cross-blade 41 normally in the position seen in Figure 6, but swingable downwardly by means of pivoted arms 42 at the ends of the platen-frame 20, and on which the blade is mounted. The blade is spring pressed, as indicated, to follow a cam 43 mounted at the end of the platen-frame 20, so that said blade, when lowered, presents its lower edge to the flared edge 39 of the apron 38 for guiding the front inserted bill-sheet downwardly past said flared edge.

The aforesaid briefly described parts relating to the sheet-insertion courses are fully described in the copending application of William F. Helmond, Serial No. 570,845, filed October 24, 1931 (now Patent No. 1,994,647, dated March 19, 1935).

Bottom feed-rolls 45 are journaled in ears 46 of the apron 38 and bear on the record-sheet 35, but only at the side margins thereof, in order to clear the bill-sheet 36, which is to be shifted crosswise of the record-sheet. For facilitating front insertion of the bill-sheet, the bottom feed-rolls 45 and the curved part of the apron 38, the latter being springy, may be cast off by means of arms 48 operable by means of a cam-shaft 49, as set forth in said Helmond application. Springs 50 bear against said arms for pressing the bottom feed-rolls 45 against the platen. As set forth in my aforesaid co-pending application, the depth of front insertion of the bill-sheet may be determined by means of a gage 51, Figure 6, against which the lower edge of the bill-sheet is initially presented.

In order that the bill 36 may be guided for collating shift, crosswise of the record-sheet 35, and be line-spaced incidentally to its crosswise shift, its upper portion is clamped, after the described front insertion of the bill, against an upstanding face of a truck 52 which runs upon a cross-rail 53 inclined as shown and mounted upon and above the platen-frame 20 in a novel manner which will presently be described. The lateral position of the bill on said truck-face is determined by means of a gage 47. By reason of the inclination of the cross-rail 53, which extends lengthwise of the platen, a shift of the bill-sheet therealong, for collation with different columns of the record-sheet, causes the truck 52 to move transversely of the platen printing-line to thereby automatically effect the line-spacing of the bill 36.

For engaging a series of position-determining

stops 54, preferably arranged in a row paralleling the platen, the bill-sheet truck 52 operative to move the bill 36 obliquely of the platen includes a tongue 55 guided for movement paralleling said row of stops; and therefore the connection between said tongue 55 and a plate 52^a forming the bill-carrying part of the truck 52 is formed as by means of a slot 56 in said plate 52^a and a roll or stud 57 of the tongue, said roll being flanged, as indicated in Figure 1, to engage opposite sides 10 of a forwardly-turned portion 58 of the plate 52^a in which said slot is formed. Such connection permits the plate 52^a and tongue 55 each to move in the direction indicated, that is, the tongue 55 moves parallel to the row of stops 54, while at the 15 same time the bill-carrying plate 52^a moves along the inclined guide-rail 53.

The truck 52 has a pair of clamp-arms 59 for clamping the bill-sheet to the upstanding plate 52^a, and, in order that said clamp-arms 59 may be 20 moved between a bill-clamping position, Figures 1 and 6, and a bill-releasing position, Figure 4, they are fastened to a cross-rod 60, journaled at one end in the plate-portion 58, and at the other end in a similar plate-portion 61. At said other end, 25 said cross-rod 60 has fastened thereto an arm 62 which coacts with a manually-operable lever 63, to enable the latter to move the clamp-arms 59 to bill-clamping or bill-releasing position, said cross-rod arm 62 and lever 63 also coacting, to detent 30 the clamp-arms in released position, as indicated in Figure 5. For running along the inclined guide-rail 53, the plate 52^a of the truck 52 has on its rear face flanged rollers 64 to engage opposite edges of the rail 53 and keep said plate on said 35 rail.

As seen in Figure 1, the platen-frame 20 has end members which may be extended as by brackets 65 to support a cross-bar 66, which, in turn, supports the inclined guide-rail 53 and also co-operates in guiding the tongue 55 of the truck 52. For the latter purpose, the cross-bar 66 may be of angle section, as indicated in Figures 1 and 6. The inner corner of the cross-bar angle presents a pair of bosses 68 spaced lengthwise of the cross-bar, as indicated in detail in Figure 9. Said bosses 68 may be attached to the cross-bar 66 by screws 69, and they may be drilled for a pair of guide-rods 70 for a structure 71, in which the tongue 55 is embodied, said guide-rods guiding the tongue 55 lengthwise of and parallel to the row of stops 54. Said structure includes a block 72, to which the rods 70 may be fastened, and from which said rods extend in opposite directions in order that preferably the rods 70 slide in the 55 bosses 68, between which said block moves, as will be evident from Figure 9.

For attaching a draw-spring 73 for urging the truck 52, which includes said structure 71 and its tongue 55, and the plate 52^a, in rightward bill-collating direction, there is fastened to one end of the pair of rods 70 a block 74, to which one end of the spring 73 is attached, the other spring-end being anchored to the cross-bar 66, as shown in Figure 9. The spring 73, disposed as shown for 65 compactness of the mechanism, passes through clearance openings in the bosses 68. The tongue 55 is secured to the block 72, and may be formed as indicated in the drawings to reach under and forwardly of the supporting cross-bar 66. A bar 70 67 rigidly connects the blocks 72 and 74 and cooperates with the rods 70 to stiffen the structure 71.

It will be evident that with the guide-rail 53 stationary, the movement of the bill-carrying

plate 52^a of the bill-truck 52, in line-spacing direction, will be proportionate to the shift of the truck lengthwise of the platen-carriage. That is, if the truck is shifted from one column of the record-sheet to an adjacent column, the plate 52^a will not be line-spaced as far as when said adjacent column is skipped for collating the bill-sheet with a column farther on along the record-sheet. It results, therefore, if the guide-rail 53 is fixed, that the line-spacing on the bill-sheet will not be uniform when columns of the record-sheet are skipped, or when for any other reason the bill-sheet is collated with the record-sheet columns not uniformly spaced crosswise of the record-sheet.

For illustration, the record-sheet, as shown in Figure 1 and in the diagrams at Figures 7 and 8, is divided into seven columns, each column representing a different item, described by the legend 20 at the head of the column. The bill-sheet is shown as having five item-spaces arranged one below another in a vertical column. Some of the item-columns of the record-sheet, as, for example, the "City Tax" and "Rural Tax" columns, 25 of Figures 1 and 7, of the "Suburban Tax" and "Rural Tax" columns, of Figure 8, are not represented on the bill-sheet and are therefore skipped in the collating operations.

Referring now to the novel arrangement 30 whereby uniform line-spacing of the items on the bill-sheet is attained, irrespective of the crosswise spacing of said items on the record-sheet, the inclined guide-rail 53 is mounted so that it may be shifted for causing retrogression of, or preventing, any skip-space-producing excess line-space movement of the bill-sheet truck 52. In order that the positions of the guide-rail 53 may be controlled by an arrangement of stops 75 similar and parallel to the stops 54, the shift of the inclined rail 53 is made to take place in a direction paralleling the platen, that is, the inclined guide-rail 53 is mounted on the platen-paralleling cross-bar 66, so as to be shiftable lengthwise of the latter. To this end, the guide-rail 53 is 40 formed as indicated in Figure 1 to include extensions 76 bearing flatwise against the front face of the cross-bar 66, and having slots 77 which slidably fit headed studs 78 projecting forwardly from said cross-bar face. For engaging the stops 75, the inclined guide-rail 53 has a forwardly-reaching tongue 79.

The stops 75 for the inclined guide-rail 53 and the stops 54 for the bill-truck 52 are in the form of arms, the guide-rail stop-arms 75 being spaced 55 along and fastened to a rock-shaft 80, and the truck stop-arms 54 being spaced along and fastened to a rock-shaft 81. Said rock-shafts are relatively disposed as indicated in Figures 1 and 6, and are journaled in brackets 82 supported by 60 a cross-member 83 which may span, and be, in turn, supported by, the arms 82 which reach forwardly from the carriage 17 to drive the totalizer-carrier 30. Each rock-shaft 80 or 81 is operative to move the corresponding stops 75 or 54 out 65 of and back into holding position for enabling the truck 52, urged by its spring 73, or the guide-rail 53, urged by a spring 85, to shift from one to another of the corresponding stops. The guide-rail spring 85 may be anchored to the 70 cross-bar 66.

The rock-shaft 80 for the guide-rail stop-arms 75 has fastened thereto, and interspaced with said stop-arms 75, other arms, namely, check-arms 86. Said check-arms 86 are so disposed 75 relatively to the stop-arms 75 that, when said

shaft 80 is rocked counterclockwise of Figure 6, to raise the stops 75 out of holding position, that is, out of the path of the tongue 79, said check-arms 86 are interposed in the path of said tongue 79 to check the spring-urged shift of the guide-rail 53 after the tongue 79 has passed the stop 75 previously engaged. It will be seen that said guide-rail 53, momentarily thus held by a check-arm 86, will be released from the latter when the rock-shaft 80 is restored by rotation clockwise of Figure 6. Upon such restoration of the rock-shaft 80, the stops 75 will also be restored, so that the tongue 79 in the resulting movement of the guide-rail 53 will engage the next stop 75. The rock-shaft 80 is yieldably held in the normal 15 angular position seen in Figure 6 by a spring 87 which pulls upon an arm 88 fastened to said rock-shaft 80, said normal position being determined as by a stop 89 of said arm 88 abutting the bracket 82, Figure 6. Since the stops 75 are 20 normally in the path of the guide-rail tongue 79, the latter is provided with a spring-pressed by-pass pawl 90, so as not to impede restoration of the shifted guide-rail. Said by-pass pawl may be arranged as indicated in Figures 1 and 2, to 25 swing about a pivot 91, but to normally stop against an edge 79^a of the tongue, whereby a stop-arm 75 or 86 is enabled to hold the guide-rail 53 against the pull of the spring 85. When returning the guide-rail 53 to its normal Figure 1 30 position, the pawl 90 swings idly about the pivot 91 while passing a stop-arm 75.

For engaging its row of stops 54, the tongue 55 of the bill-truck 52 is also provided with a by-pass pawl 92, so that said stops 54 may not 35 impede return of the shifted truck. The truck-controlling rock-shaft 81 also has check-arms 94 interspaced with its stop-arms 54, and it will be evident that the operation and relative arrangement of said rock-shaft 81, its arms 54 and 40 94, and of the pawl 92, are similar to the operation of the described similar parts for the guide-rail 53. The rock-shaft 81 is yieldably held in normal position by a spring 93, said normal position being determined by abutment of an arm 95 45 of said shaft against a stop 95^a.

Each stop-arm 54 and 75 has its tongue-engaging stop-surface extended in the direction of platen case-shift movement, as indicated in Figure 1, so that, when the platen is in upper-case 50 position, said stop-arms will still be effective to hold the truck 52 and guide-rail 53.

It is provided that the recollation of the bill and record sheets between the typings of items may be effected by the operation of only one 55 key-mechanism, and that said key-mechanism may be the conventional tabulating key or keys of the typewriter 15, and that, furthermore, to expedite the recollating operations, a denominational tabulating mechanism is used. Referring 60 to Figure 2, 96 represents the usual Underwood denominational tabulating keys, which are mounted upon the usual tabulating-key levers not shown, but which extend rearwardly to elevate the usual denominational stop-blades 97 65 into the path of column-stops 98, settable along a rack 99 carried by the typewriter-carriage 17. At the operation of any tabulating key 96, the carriage 17 will be released from the escapement-devices 25 when a corresponding stop-blade 97 70 is elevated, whereupon the carriage 17 will advance under the pull of the carriage-motor 24 until arrested by means of the elevated stop-blade 97 and a column-stop 98. The denominational tabulating mechanism thus serves between 75

the typings of the items to advance the appropriate item-columns of the record-sheet 35 to the printing-point.

In order that the same operation of the denominational tabulating keys 96 that brings a new record-sheet column to the printing-zone may effect the necessary recollation of the single vertical column of the bill-sheet 36 with the new record-sheet column which has been advanced to the printing-point, the tabulating movement of the carriage 17 resulting from said tabulating-key operation is utilized to automatically actuate the bill-truck position-controlling rock-shaft 81. Said rock-shaft 81 has accordingly fastened thereto a set of forwardly-extending tappet-arms 100 arranged so as to pass and be displaced by a fixed non-traveling cam, preferably a cam-roll 101. In order that said cam-roll 100 may be effective in the advance of the carriage 17 in tabulating direction, but be diverted by the tappet-arms 100, so as not to actuate the latter in the return movement of the carriage, said cam-roll 101 may be mounted upon a pawl 102.

Said cam-roll pawl 102 is pivoted at 103 upon a bracket 104, fastened to the non-traveling track 29 for the totalizer-carrier 30. A stop 102^a of said pawl abutting said bracket 104 holds the pawl 102 so that the cam-roll 101 may be effective for rocking the shaft 81 by the advance of the carriage in tabulating direction. In the return movement of the carriage, the pawl 102 will be idly diverted by the tappet-arms 100, swinging about its pivot against the pull of a pawl-spring 105 which serves to restore the diverted pawl to the normal Figure 2 position.

It has been explained that the line-spacing movement of the bill-sheet 36 is proportionate to the rightward shift of the bill-truck 52, by reason of the inclination of the guide-rail 53. If the bill-truck stops 54 are uniformly spaced, as in accordance with uniformly-spaced record-sheet columns, and, furthermore, if, at each tabulation of the carriage 17, the rock-shaft 81 is actuated by means of the cam-roll 101 to bring successive ones of said truck-stops 54 into use, then the items on the bill-sheet will be uniformly line-spaced, assuming that, following each tabulating-key operation, an item is typed.

Should the record-sheet, however, have columns for an item which is not to be entered on the bill-sheet, as, for example, the "City Tax" column of Figure 7, then, following the typing of the "State Tax" item, a tabulating key 96 is operated to first tabulate the carriage 17 to advance the "City Tax" record-sheet column to the printing-zone, and then the appropriate denominational key is operated to bring the "Suburban Tax" record-sheet column to the printing-zone. It will be obvious that, if the inclined guide-rail 53 remains stationary during the described two operations of the tabulating keys 96 between the typings of the "City Tax" and the "Suburban Tax", the bill-sheet 36 will have been advanced in line-spacing direction an extra-line-space. That is, the spacing between the "State Tax" and "Suburban Tax" items on the bill-sheet will be greater than the spacing between the "Flat Water" (the first item typed) and "State Tax" items.

In order to effect uniform line-spacing of the bill-sheet items when a record-sheet column is skipped, the guide-rail 53 is caused to be shifted by actuating its position-controlling rock-shaft 80 whenever a column on the record-sheet is skipped in the tabulating operations. For this

purpose, the carriage-movement resulting from said tabulating operations is utilized to actuate the guide-rail-controlling rock-shaft 80 which has accordingly fastened thereto a suitable number of tappet-arms 106, one for each shift of the guide-rail 53 required during the typing of a bill-sheet 36 and a corresponding line on the record-sheet 35. Said tappet-arms 106 may be arranged as indicated in Figures 1 and 6, so that they may be operated by the same cam-roll 101 that operates the tappet-arms 100 of the truck-controlling rock-shaft 81.

Assuming that, between the typings of successive items, a column of the record-sheet has been skipped, the tappet-arm 106, provided and suitably located on the rock-shaft 80 for this contingency, will, during the tabulating advance of the carriage occurring between the typings of said two items, have been actuated by the cam-roll 101, thereby causing the guide-rail stops 75 to be raised and lowered again, and in consequence the guide-rail 53, urged by its spring 85, will move rightwardly from one stop 75 to another stop 75, it being understood that, following the escape of the guide-rail ensuing upon the raising of said stops 75, the guide-rail shift is momentarily checked before its completion by the raised check-arm 86 until the stops 75 are lowered again. By reason of such rightward shift of the guide-rail 53 from one to a succeeding one of the stops 75, during column-skipping, the net result of the movement of the bill-carrying plate 52^a in line-spacing direction, relative to said guide-rail 53, will be as though the bill-truck 52 was only shifted from one record-sheet column to an immediately adjacent column, and therefore no skip-space will appear in the line-spacing of the bill-sheet items.

It will be understood that the truck-controlling stops 54, the guide-rail-controlling stops 75, and the tabulating column-stops 98 may be arranged in different ways in accordance with the arrangement of the record and bill sheets. For example, Figures 1, 2 and 5 show an arrangement of stops whereby, in order to make said arrangement universal for any bill-sheet and record-sheet arrangement, there is provided a column-stop 98 for each record-sheet column, and there is also provided for each record-sheet column a stop 54, wherefore skipping of a record-sheet column entails repeated operation of the tabulating keys 96. According to such universal arrangement such number of guide-rail stops 75 may be provided as will effect one stage of guide-rail shift for each record-sheet column that is to be skipped in the typing of a bill.

It will be understood, however, that the arrangement of the stops with respect to their number and disposition, as shown in Figures 1, 2 and 5, may be modified. Thus, for example, as indicated in Figure 3, and considering the items of the bill-sheet and their disposition on the record-sheet as seen in the diagram at Figure 7, the column-stops 98 (those indicated by the dotted lines) may be omitted for the "City Tax" and "Rural Tax" columns. Corresponding ones of the truck-shift-controlling stops 54 may also be left out, the omitted stops 54 being indicated by the dotted lines in Figure 3. Still referring to the diagram at Figure 7, it will be noted that two stages of guide-rail shift are required since, between the skipped "City Tax" and "Rural Tax" columns, there is the "Suburban Tax" column, in which, and in a corresponding space on the bill-sheet, an item is typed. Three 75

guide-rail stops 75, and two tappet-arms 106, determining said two stages, are therefore indicated in the Figure 3 diagram. For clearness, the check-arms 86 and 94 associated respectively with the stops 75 and 54 are not shown in the Figure 3 diagram.

Figure 8 exemplifies a form of bill and record-sheet wherein two record-sheet columns, namely, "Suburban Tax" and "Rural Tax", are skipped 10 in the tabulating operation occurring between the typings of the "City Tax" and "Paving Tax". If, for the skipping of said two record-sheet columns, corresponding column-stops 98 and truck-stops 54 are omitted in an arrangement similar to 15 that illustrated in the diagram at Figure 3, there will be only one stage of column-skipping, and therefore there need be only one stage of shifting the guide-rail 53, and hence only two guide-rail stops 75 and one tappet 106 for determining 20 said one stage of guide-rail shift will be needed.

The several stop-arms 54, 75, the check-arms 25 94, 86, and the tappet-arms 100, 106 may be releasably secured to the shafts 80, 81, as by set-screws 119 and 120, Figure 6. It will be evident 30 that omission of the use of any one of these arms may be effected by swinging the same to ineffective position, so as to clear the tongues 55 and 79 of the bill-sheet truck and guide-rail, respectively. From the foregoing, it will be evident 35 that the invention is not limited to the arrangements of the several stop-arms shown.

It may be noted, since the truck-stops 54 or 75 are, during the recollating operations, only momentarily out of effective position, the same being 40 restored as soon as a tappet-arm 100 or 106 passes the cam-roll 101, that, in some cases, the check-arms 86 and 94 may be omitted, as, for example, where the spacing between successive stops 54 or 75 is of such extent that said stops 45 will have ample time to return before the truck 52 or guide-rail 53 reaches the stop 54 or 75 following the one from which it was released.

For returning the bill-truck 52 to its normal 50 position relative to the typewriter-carriage 17 after the typing of a bill, a handle or finger-piece 117 is provided, and may be attached, as indicated in Figure 9, to the bar 67 of the tongue-structure 71 of said truck 52. Said finger-piece 117 also serves to return the guide-rail 53 to its 55 normal position with the same stroke of the hand that returns the truck 52, and for this purpose the plate 52^a of said truck may have a projection 114, Figure 1, which engages an edge 53^a of the guide-rail 53, and thereby moves the latter along back to normal position when the truck 52 is fully returned.

The totalizer-heads 31, one for each kind of item, are used for footing the items of the individual record-sheet columns. Each item in the 60 last record-sheet column represents the total of a bill, and said total is computed in a cross-totalizer 107 afforded by the computing base 16 and operated in conjunction with the operation of the totalizer-heads 31 in the manner set forth 65 in the co-pending application of Thieme, Serial No. 680,036, filed July 12, 1933. Briefly described, therefore, as an item is typed and entered one figure at a time in the corresponding totalizer-head 31, indexing-devices for the totalizer 107 70 are set up in the computing base 16 by means of the numeral-keys 26^a and denomination-selecting trains represented by jacks 109, Figure 6. Said jacks are operable seriatim by computing-zone tappets 110, one for each item, on the carriage 75 17. As the carriage advances a letter-feeding

step after typing the last figure of an item in a computing zone, the column-stop 98 for said zone may actuate a train 111, diagrammatically indicated in Figure 6, to trip cycling mechanism not shown but represented by said train 111. By the 5 tripping of such cycling mechanism, the amount indexed by the numeral-keys 26^a is caused to be run into the cross-totalizer 107. The last or "Total Tax" item on the bill-sheet and on the record-sheet is copied from the cross-totalizer 107, and, preparatory to such copying, the mechanism in the computing base is automatically set for subtraction by means of a cam 112 on the last column-stop 98, said cam operating a train 113 to set the computing base 16 for subtraction 11 in the manner set forth in Minton Patent No. 1,280,065, which also shows the denomination-selecting trains. By reason of said subtraction-setting, the cross-totalizer 107 will be cleared for the next bill when the computing base 16 is cycled 21 following the copying of the "Total Tax" item.

The typewriter-carriage 17 has the usual line-spacing mechanism 115 including a carriage-returning and line-spacing handle 116.

The operation of the machine will be readily 25 understood from the foregoing description, and may therefore be summarized as follows.

Referring to Figure 7, it is indicated by the four transverse lines of items that four bills have 30 already been typed, and the like items have been entered in the appropriate record-sheet columns, and that the typing of the first item, "Flat Water", for the fifth bill is just about to be completed. Following the typing of said first item, the computing base 16 is cycled, as explained, and the appropriate denominational tabulating key 96 is operated to advance the carriage 17 to bring the "State Tax" column of the record-sheet, for which there is a column-stop 98, to the printing and computing zone. By such tabulating movement of the carriage 17 the bill-truck 52 may be temporarily carried along to an extent depending on the relative positions of the first tappet-arm 100 and roller 101. The first tappet-arm 100 is so disposed on the rock-shaft 45 81 that the latter is caused to be rocked first in one direction to raise the stop-arms 54 and check-arms 94 as said tappet-arm passes under the cam-roll 101 and then is rocked in the opposite direction under the pull of the shaft-spring 50 93 to restore said arms 54, 94 as said tappet-arm 100 passes beyond said cam-roll 101 before said tabulating movement is completed, thereby causing the bill-truck 52 to move rightward under the pull of its spring 73 to the position determined 55 by the next truck-stop 54. By said rightward movement of the bill-truck 52 relative to the carriage 17, the single bill-sheet item-column is recollated with the "State Tax" column of the record-sheet, and incidentally the bill-sheet-carrying plate 52^a is moved in line-spacing direction, by reason of the inclination of the guide-rail 53 along which said plate 52^a runs in said rightward movement of the truck. The recollating and line-space shift of the "State Tax" space 60 of the bill-sheet to the "State Tax" column thus effected is indicated in Figure 7 by the graph 118.

It will be understood that, during the typing 65 of each item, the bill-truck 52 moves in letter-feeding unison with the carriage 17, by reason 70 of the coupling effected by means of the truck-tongue 55 and whichever stop 54 said tongue abuts.

The "State Tax" space in the single column of 75 the bill-sheet having been collated with the

"State Tax" column of the record-sheet, the "State Tax" item is now typed, the computing base 16 being again cycled for entering the "State Tax" in the cross-totalizer 107. Since the 5 "City Tax" is not represented on the bill-sheet 36, the "City Tax" column of the record-sheet is to be skipped in the tabulating operation following the typing of the "State Tax". For skipping the record-sheet "City Tax" column, any 10 one of the tabulating keys 96 may be operated. In the resulting tabulating movement of the carriage 17, the second tappet-arm 100 of Figure 2 will pass underneath the cam-roll 101, thereby causing the bill-truck 52 to move from the second 15 bill-truck stop 54 of Figure 2 to the third bill-truck stop 54. The proper denominational key 96 is now operated to bring the "Suburban Tax" column of the record-sheet to the printing-zone, and, during the resulting tabulating movement of 20 the carriage, the third tappet-arm 100 of Figure 2 will pass under the roll 101, hereby causing a shift of the bill-truck 52 to the fourth truck-stop 54 of Figure 2. The single bill-sheet column will thus have been collated with the "Suburban 25 Tax" column of the record-sheet.

Incidentally to the described repeated operations of the tabulating keys 96 resulting in shifting said single bill-sheet column, first to the "City Tax" column of the record-sheet, and then 30 to the "Suburban Tax" column of the record-sheet, the guide-rail 53 will have been shifted, and, to this end, a guide-rail-shift-controlling tappet-arm 106 is disposed so as to pass under and be rocked by the cam-roll 101, either during 35 the shift from the "State Tax" to the "City Tax" column, or during the shift from the "City Tax" column to the "Suburban Tax" column. As indicated in Figure 2, the tappet-arm 106 is disposed adjacent to the second tappet-arm 100 40 which controls the truck-shift, so that the guide-rail shift takes place during the shift of the truck from the "State Tax" to the "City Tax" column. By the shifting of the guide-rail 53 rightward relative to the carriage 17, the skip- 45 space producing excess of line-space movement incident to the skipping of the "City Tax" column is negated, as is indicated by the break 121 in the graph 122 of Figure 7, said graph indicating the collation of the "Suburban Tax" 50 space on the bill-sheet with the "Suburban Tax" column on the record-sheet. The graph 122 also includes, as will be readily noted, a portion corresponding to the previous graph 118. In the described shift of the guide-rail 53 attending the 55 skipping of the "City Tax" column of the record-sheet, said guide-rail will move from the first stop 75 to the second stop 75 of Figure 2, it being obvious that the operation of the guide-rail rock-shaft 80 and its arms 75, 85, by means of the 60 tappet-arm 106, will be similar to the described operation of the rock-shaft 81.

The "Suburban Tax" is now typed, and, following this, there is a repeated operation of the tabulating keys 96 to bring the "Paving Tax" 65 space of the bill-sheet to the "Paving Tax" column of the record-sheet, the repetition of said tabulating-key operation being necessary to skip the "Rural Tax" column (for which there is no space on the bill-sheet). During said repeated 70 tabulation, the guide-rail 53 is again shifted by means of the second tappet-arm 106, Figure 2, to negative the skip-space producing excess of line-space movement of the bill-sheet resulting from skipping the "Rural Tax" column. The 75 guide-rail, by such shift, comes in contact with

the third guide-rail stop 75, and the truck 52 will of course have been advanced to the sixth truck-stop 54 of Figure 2 by the repeated tabulating-key operation. The collation of the "Paving Tax" bill-sheet spaced with the record-sheet "Paving 5 Tax" column is indicated by the graph 123 which includes a break 124 to represent the shift of the guide-rail attending the skipping of the "Rural Tax" column, it being understood that the graph 123 includes the previous graphs 118, 122. Similarly the bottom graph 125 includes the previous graphs and also the portion indicating the collation of the "Total Tax" bill-sheet space with the "Total Tax" record-sheet column. 10

For the "Total Tax" collation, the appropriate 15 tabulating key 96 will be operated, thereby causing the last tappet-arm 100 to pass under the roll 101 and resulting in the truck 52 escaping to the last column-stop 54. The "Total Tax" is now copied on the sheets 35, 36 from the cross-totalizer 107 and incidentally entered into a corresponding vertical totalizer-head 31, it being understood that each record-sheet column in which an item is typed is represented by a totalizer-head 31. Following the typing of the "Total 20 Tax" item, the computing base is subtractively cycled as already explained, thereby causing the cross-totalizer 107 to be cleared. A proof-key 126 may be operated to print a clear sign verifying the correct transcription of the total shown by 25 the cross-totalizer 107.

In the diagram at Figure 7, the lines 127 represent the addition of the items of a bill by the cross-totalizer 107, the last line 127a representing the subtraction of the "Total Tax" item from said 30 cross-totalizer 107.

The typewriter-carriage 17 is now returned, and incidentally to such return, by means of the line-space handle 116, the record-sheet 35 will be line-spaced for a new bill 36. The typed bill is 40 removed from the bill-truck 52, and, before the new bill is inserted, the bill-truck resting against the last stop 54 is returned to its normal position relative to the carriage 17 by means of the handle 117, in order to bring the bill-receiving plate 52a 45 in proper relation to the bill-gage 51. Incidentally to such return of the bill-truck, the guide-rail 53 will also be returned to its normal position, determined by the first stop 75.

From the foregoing, it will be evident that the 50 operation of the machine for producing a bill and record-sheet having the forms represented in the diagram at Figure 8, will be effected similarly to the operation just described with reference to the sheet-forms of Figure 7, it being noted, however, 55 that the guide-rail-controlling tappet-arms 106 will be positioned on the rock-shaft 80 in such wise as to cause the guide-rail 53 to be shifted when the "Suburban Tax" and the "Rural Tax" record-sheet columns, Figure 8, are skipped. The 60 graphs 128 in Figure 8 represent the bill-sheet collating movements of the truck-plate 52a, it being noted that the two lower graphs 128 include portions 128a representing each a line-space-modifying shift of the guide-rail 53, the shift of the 65 bill-sheet from the "City Tax" record-sheet column to the "Paving Tax" column being effected in two stages by repeated operation of the tabulating keys 96.

As already explained, Figure 3 represents an arrangement of stop-arms designed to avoid repetition of operating the tabulating keys 96 when a column is to be skipped, and it will be understood that operation of the machine with reference to a stop-arrangement such as shown in 70 75

Figure 3 is, aside from avoiding repetition of tabulating-key operation, similar to the operation of the machine described with reference to Figure 7. The by-pass pawls 90 and 92 may each be provided with an anti-friction roller 130 for contacting the stops 75 and 54 to ease the operation of the shafts 80, 81 by means of the movement of the typewriter-carriage 17.

For preventing springing of the left end of the tongue-structure 71 of the truck 52 when the operator's hand is applied to the handle 117 for returning the truck, said handle may carry a roller 131 which bears on the top of the cross-bar 66 and also bears against an edge of a strip or ridge 132 of the cross-bar 66, see Figures 1 and 4.

Variations may be resorted to within the scope of the invention, and portions of the improvements may be used without others.

Having thus described my invention, I claim:

1. In a machine, having types, for typewriting-manifolding a bill-sheet with a record-sheet, the combination of a carriage for the record-sheet, a truck for the bill-sheet, said carriage and truck mounted for letter-feeding movement in unison, and also for movement relative to one another and to the types, so that items typed, one under another, in a single column of the bill-sheet are at the same time manifolded alongside one another in different columns on the record-sheet, a single set of denominational tabulating keys, and means whereby, at the operation of any tabulating key, following the printing of an item on the bill-sheet and in a column of the record-sheet, said record-sheet carriage is tabulated to bring a corresponding denomination of a succeeding record-sheet column to the printing-point, and whereby, as a result of said tabulating-key operation, the bill-truck is automatically positioned relatively to the record-sheet carriage to bring the same denomination in the bill-sheet column to said printing-point.

2. In a machine, having types, for typewriting-manifolding a bill-sheet with a record-sheet, the combination of a letter-feeding carriage for the record-sheet, a truck for the bill-sheet, means for effecting coupling of the truck to said carriage in different positions relative to the latter, so that items typed one below the other in a single column of the bill-sheet are at the same time manifolded alongside one another in different columns on the record-sheet, a single set of denominational tabulating keys, and means whereby, at the operation of any tabulating key, following the printing of an item on the bill-sheet and in a column of the record-sheet, said record-sheet carriage is tabulated to bring a corresponding denomination of a succeeding record-sheet column to the printing-point, and whereby, as a result of said tabulating-key operation, said coupling means are automatically actuated to reposition the truck relative to the record-sheet carriage, to bring the same denomination in the bill-sheet column to said printing-point, means being provided to automatically effect line-spacing of the bill-sheet.

3. In a machine, having types, for typewriting-manifolding a bill-sheet with a record-sheet, the combination of a letter-feeding carriage for the record-sheet, a truck for the bill-sheet, means for effecting coupling of the truck to said carriage in different laterally and vertically spaced relations to the carriage so that items will be typed one below the other in a single column of the bill-sheet, and will at the same time be manifolded alongside one another in different columns on the record-

sheet, a single set of denominational tabulating keys, and means, whereby, at the operation of said tabulating key following the printing of an item on the bill-sheet and in a column on the record-sheet, said record-sheet carriage is tabulated to bring a corresponding denomination of a succeeding record-sheet column to the printing-zone, and whereby, as a result of said tabulating-key operation, said coupling means are automatically actuated to reposition the truck relative to the record-sheet carriage, to bring the same denomination in the bill-sheet column to said printing zone and to change the vertically-spaced relation of the truck and carriage to effect line-spacing of the bill-sheet.

4. In a typing machine, the combination of a tabulating carriage for a record-sheet upon which different items are typed in corresponding vertical columns, a truck constantly urged to move lengthwise of said carriage in a direction opposite to the tabulating movement of the latter, and arranged to present a second work-sheet in manifolding relation to the record-sheet, the items being typed on said second sheet one below the other in a single column, a series of stops for restraining the truck and determining, by means of one or another thereof, the position of the truck relative to said carriage, said truck and carriage being coupled by means of said stops to advance in unison for letter-feeding, and tappet-means whereby the carriage, by its movement to tabulate successive columns of the record-sheet to the printing-zone, automatically causes said truck to be repositioned, at each column, relatively to said carriage by means of said stops, whereby, as each column of the record-sheet is tabulated to the printing-zone, the single column of the second work-sheet is automatically collated with said each record-sheet column.

5. A machine, having types, for typewriting-manifolding a bill-sheet and a record-sheet, including a carriage for presenting the record-sheet to the types, a truck for presenting the bill-sheet in manifolding relation to the record-sheet and types, said bill-sheet truck being shiftable lengthwise of the carriage to collate a single column of the bill-sheet in which items are entered one below the other with a multiplicity of item-classifying columns spaced transversely of the record-sheet, and means whereby the movements of the truck for shifting same lengthwise of the carriage to collate the single bill-column with different record-sheet columns automatically effects line-spacing of the bill-sheet, said line-space-effecting means being arranged so that the items on the bill-sheet are uniformly line-spaced irrespective of uniformity or non-uniformity of the spacing of the record-sheet columns in which said items are entered.

6. A machine, having types, for typewriting-manifolding a bill-sheet and a record-sheet, including a carriage for presenting the record-sheet to the types, a truck for presenting the bill-sheet in manifolding relation to the record-sheet and types, said bill-sheet truck being shiftable lengthwise of the carriage to different stop-positions to collate a single column of the bill-sheet in which items are typed one below the other with a multiplicity of different item-classifying columns of the record-sheet, and means whereby, at each shift of the bill-truck from one stop-position to another, the bill is line-spaced, the bill-truck being repeatedly shiftable to skip a record-sheet column, said line-space means being arranged so that, when a column is skipped, the

line-spacing of the bill-sheet incident to such 5 skipped column is automatically negated, whereby the line-spacing of the bill-sheet items is uniform irrespective of the transverse spacing of the columns of the record-sheet in which said items are entered.

7. In a typing machine, the combination with the types, of a tabulating carriage arranged to present to the types a record-sheet having a multiplicity of item-classifying columns spaced different distances apart crosswise of the record-sheet, a truck for presenting a bill-sheet, having a single item-column in which items are typed one below the other, in manifolding relation to said record-sheet, said truck being movable lengthwise of the carriage for locating the bill-truck at different positions, corresponding to the unequally-spaced record-sheet columns, lengthwise of the carriage, and means whereby the movements of the truck in its shifts to successive unequally-spaced positions automatically causes the bill to be uniformly line-spaced.

8. In a typing machine, the combination with the types, of a tabulating carriage arranged to present to the types a record-sheet having a multiplicity of item-classifying columns spaced different distances apart crosswise of the record-sheet, a truck for presenting a bill-sheet, having a single item-column in which items are typed one below the other, in manifolding relation to said record-sheet, said truck being movable lengthwise of the carriage for locating the bill-truck at different positions, corresponding to the unequally-spaced record-sheet columns, lengthwise of the carriage, a camming device automatically effective, in the shifts of the truck to successive positions relative to the carriage, to cam the truck in line-spacing direction, said camming device arranged to cam the truck in uniform ratio to its shift lengthwise of the carriage, in order to provide for line-spacing the truck uniformly as for equally-spaced record-sheet columns, and means whereby, in tabulating the carriage with reference to two successive record-sheet columns whose spacing varies from the equally-spaced columns, said camming device is automatically shifted to maintain said uniformity of the line-spacing.

9. In a typing machine having types, the combination of a paper-carriage for presenting a work-sheet to the types, a truck for presenting a second work-sheet in manifolding relation to the first work-sheet, means including an inclined guide-rail operative for guiding said truck for movement relative to said carriage whereby an item-column of the work-sheet on said truck may, by shifts of the truck relative to said carriage, be collated at different item-columns spaced crosswise of the first work-sheet, and may also be line-spaced incidentally to said shifts, and means for effecting a displacement in said truck-guiding means with reference to said inclined guide-rail, whereby unequal shifts of the truck for collating its work-sheet with unequally-spaced columns of the first work-sheet will nevertheless effect equal displacements of the truck in line-spacing directions.

10. In a typing machine having types, the combination of a paper-carriage for presenting a work-sheet to the types, a truck for presenting a second work-sheet in manifolding relation to the first work-sheet, a guide-rail inclined relatively to the printing-line of the first work-sheet, and along which said truck runs in shifts effected for collating an item-column of the work-

sheet on said truck with successive item-columns of the first work-sheet, the inclination of said guide-rail being effective to line-space the truck incidentally to each of said shifts, said shifts being of unequal extents corresponding to unequal spacing of the columns of the first work-sheet, and means operative for displacing said guide-rail in accordance with the inequality in the collating shifts of said truck, thereby to effect uniform line-spacing of the work-sheet on said truck.

11. In a typing machine having types, the combination of a paper-carriage for presenting a work-sheet to the types, a truck for presenting a second work-sheet in manifolding relation to the first work-sheet, means for guiding said truck for movement relative to said carriage, whereby an item-column of the work-sheet on said truck may, by shifts of the truck relative to said carriage, be collated with different item-columns spaced crosswise of the first work-sheet, and may also be line-spaced incidentally to said shifts, and means including stops for effecting displacement, gaged by said stops, of said truck-guiding means, whereby unequal shifts of the truck for collating its work-sheet with unequally-spaced columns of the first work-sheet will nevertheless effect equal displacements of the truck in line-spacing direction.

12. In a typing machine having types, the combination of a paper-carriage for presenting a work-sheet to the types, a truck for presenting a second work-sheet in manifolding relation to the first work-sheet, means for guiding said truck for movement relative to said carriage, whereby an item-column of the work-sheet on said truck may, by shifts of the truck relative to said carriage, be collated with different item-columns spaced crosswise of the first work-sheet, and may also be line-spaced incidentally to said shifts, and means including stops for effecting displacement, gaged by said stops, of said truck-guiding means, whereby unequal shifts of the truck for collating its work-sheet with unequally-spaced columns of the first work-sheet will nevertheless effect equal displacements of the truck in line-spacing direction, said last-mentioned means being arranged so as to be automatically operated at predetermined points in the travel of said carriage.

13. In a typing machine having types, the combination of a paper-carriage for presenting a work-sheet to the types, a truck for presenting a second work-sheet in manifolding relation to the first work-sheet, a member mounted on said carriage and co-operative with a part on said truck for guiding said truck for oblique movement relative to said carriage, whereby an item-column of the work-sheet on said truck may, by shifts of the truck relative to said carriage, be collated at different item-columns spaced crosswise of the first work-sheet, and may also be line-spaced incidentally to said shifts, means constantly urging displacement of said guide-member relative to said carriage, and stop-means normally restraining said member and operable to effect and gage said displacement, whereby unequal shifts of the truck for collating its work-sheet with unequally-spaced columns of the first work-sheet will nevertheless effect equal movements of the truck in line-spacing direction.

14. In a typing machine having types, the combination of a paper-carriage for presenting a work-sheet to the types, a truck for presenting a second work-sheet in manifolding relation to

- the first work-sheet, a member mounted on said carriage and co-operative with a part on said truck for guiding said truck for oblique movement relative to said carriage, whereby an item-
 5 column of the work-sheet on said truck may, by shifts of the truck relative to said carriage, be collated at different item-columns spaced cross-wise of the first work-sheet, and may also be line-spaced incidentally to said shifts, means
 10 constantly urging displacement of said guide-member relative to said carriage, stop-means normally restraining said member and operable to effect and gage said displacement, and a tap-pet-device whereby the carriage at a predetermined point in its travel operates said stop-means to effect a displacement of said guide-member, whereby unequal shifts of the truck for collating its work-sheet with unequally-spaced columns of the first work-sheet will nevertheless effect
 15 equal movements of the truck in line-spacing direction.
15. In a typewriting machine, the combination of a carriage for presenting to the types a record-sheet having a plurality of item-classifying columns, a truck for presenting a bill-sheet in manifolding relation to the record-sheet, said truck shiftable relatively to the carriage for collating a bill-sheet column, in which different items are typed one below another, with corresponding record-sheet columns, means tending to line-space the bill-sheet in proportion to the shift of the truck lengthwise of the carriage, whereby, for entries of items in uniformly-spaced record-sheet columns, the corresponding items on the bill-sheet are uniformly line-spaced, and means operable to act on said line-spacing means to modify the line-spacing when, between the typings of successive items, the truck is shifted lengthwise of the carriage for entry of said successive items in record-sheet columns that are differently spaced, whereby the items are uniformly line-spaced on the bill-sheet irrespective of the spacing of corresponding record-sheet columns.
- 45 16. A machine constructed according to claim 15, and including a tabulating mechanism for said carriage, whereby, following the typing of an item in one record-sheet column, the carriage is tabulated to bring a new record-sheet column to the types, and means automatically brought into use at the operation of said tabulating mechanism to cause the bill-sheet truck to be correspondingly shifted, and also to cause said line-space-modifying means to be operated to act on said line-spacing means if the carriage and truck-shifts resulting from said tabulating-mechanism operation are made with reference to said differently-spaced record-sheet columns.
17. In a typing machine, the combination with
 60 a platen for presenting a record-sheet to the types, of a truck for presenting a bill-sheet in manifolding relation to the record-sheet, a member engaging a part of said truck for guiding said truck for shifts relative to the platen in a direction oblique to the printing-line, said shifts effective to collate a bill-sheet column in which items are typed one below another with different item-classifying columns of the record-sheet, said oblique direction of the truck-shifts being effective to also line-space the bill-sheet proportionately to the movement of the truck from column to column of the record-sheet, and means operable incidentally to any shift of the truck to effect a bodily relocation of said guiding member
 70 relative to said platen, whereby the line-spacing
 75

of the items of the bill-sheet is rendered comparatively dissentaneous with the spacing of the record-sheet columns.

18. In a typing machine, the combination with a platen for presenting a record-sheet to the types, of a truck for presenting a bill-sheet in manifolding relation to the record-sheet, a member engaging a part of said truck for guiding said truck for shifts relative to the platen in a direction oblique to the printing-line, said shifts effective to collate a bill-sheet column in which items are typed one below another with different item-classifying columns of the record-sheet, said oblique direction of the truck-shifts being effective to also line-space the bill-sheet proportionately to the movement of the truck from column to column of the record-sheet, key-operated tabulating mechanism operable, preparatory to the typing of an item in the bill-sheet column and in the corresponding record-sheet column, to effect the tabulation of said record-sheet column with the types, and to correspondingly effect a shift of the truck to collate the bill-sheet with said record-sheet column, and means operable incidentally to any tabulating operation to effect a bodily relocation of said guiding member relative to said platen, whereby the line-spacing of the items on the bill-sheet is rendered comparatively dissentaneous with the spacing of the record-sheet columns.

19. A machine constructed according to claim 18, including means whereby said guide-member-relocating means are automatically operated at the tabulating operation executed preparatory to typing a certain one of the items.

20. The combination of a carriage for a multiple-column record-sheet, a bill-sheet carrier repeatedly shiftable laterally of said carriage to collate a single column of the bill-sheet with successive record-sheet columns, a cam-connection, between said carriage and carrier, normally effective to line-space the bill-sheet in proportion to each lateral shift of said carrier relatively to said record-sheet, whereby even lateral shifts of the bill-carrier result in even line-spacing of the bill-sheet, means operable to substantially disable said cam-connection for a portion of an extended shift, such as a column-skipping shift, of the bill-carrier, to preserve the even line-spacing, and means settable to predetermine automatic operation of said disabling means at and only for an extended shift of the bill-carrier.

21. The combination of a record-sheet carriage, a bill-sheet carrier repeatedly shiftable laterally relatively to said carriage for collating a single column of a bill-sheet successively with a multiplicity of columns of the record-sheet, and means operating automatically at successive lateral shifts of the bill-carrier relatively to the carriage to uniformly line-space the bill, said line-spacing means being arranged to automatically maintain the uniform line-spacing for column-skipping shifts as well as for shifts effected relatively to adjacent record-sheet columns.

22. The combination of a record-sheet carriage, a bill-sheet carrier repeatedly shiftable laterally relatively to said carriage for collating a single column of a bill-sheet successively with a multiplicity of columns of the record-sheet, said bill-carrier being also shiftable for line-spacing, a device on the carriage, extending in the direction of bill-carrier shifts, and means on the bill-carrier interacting with said device so that the lateral collating shifts of the bill-car-

rier relatively to the carriage produce line-spacing shifts of said bill-carrier, and means for displacing said device, relatively to the means interacting therewith, for limiting the line-space shift at an extended lateral shift of the carrier, as for column-skipping, whereby uniform line-spacing results irrespective of whether or not the several bill-carrier lateral shifts include a column-skipping shift, said device and the there-with interacting means remaining effective, after their relative displacement, for continuing the uniform line-spacing.

23. The invention as set forth in claim 22 inclusive of means operative to concomitantly return the bill-carrier to an initial position relatively to the carriage, and relatively restore said device and the therewith interacting means if displaced as aforesaid.

24. The combination of a tabulating carriage

for a multiple-column record-sheet, a bill-sheet carrier repeatedly shiftable laterally relatively to the carriage, at the tabulating advances of the latter for successive record-sheet columns, to collate the bill-sheet with said columns, an inclined track on the carriage effective, at each lateral shift of the bill-carrier relatively to the carriage, to shift said bill-carrier in line-spacing direction, means operable for displacing said track relatively to the carriage, whereby, if a carriage advance is for column-skipping, the line-spacing for said column-skipping advance is negatived, thereby to provide for uniform line-spacing of the bill-sheet, and means co-operative with the carriage at a column-skipping advance of said carriage to automatically operate said track-displacing means.
